UNITED STATES PATENT OFFICE

HARRY E. MENG, OF OAK PARK, ILLINOIS, ASSIGNOR TO THE W. D. ALLEN MANUFACTURING COMPANY, OF CHICAGO, ILLINOIS, A CORPORATION

SPRINKLER HEAD

Application filed July 11, 1932. Serial No. 621,783.

This invention relates to the art of lawn sprinklers, and, while adaptable for use in connection with any known type of lawn sprinkler, has more particular reference to 5 lawn sprinklers of the type wherein a plurality of sprinkler heads are interposed in a length of hose, so as to increase the sprinkling area and obviate the necessity of frequently shifting a single sprinkler head to various 10 positions on the lawn.

The main purpose or object of the present invention has been to provide a sprinkler head of very simple and economical construction, and which may obviate the use of a 15 multiplicity of assembled parts and packings to prevent leakage.

A preferred embodiment of the invention is illustrated in the accompanying drawing in which—

20 Fig. 1 is a top plan view of the sprinkler head and its support.

Fig. 2 is an enlarged vertical transverse section on the line 2—2 of Fig. 1.

25 Fig. 3 is an enlarged longitudinal vertical section viewed on the line 3—3 of Fig. 1, with the tube section omitted.

Fig. 4 is an enlarged longitudinal vertical section viewed on the line 4—4 of Fig. 1, with the tube section omitted.

30 Fig. 5 is an enlarged horizontal longitudinal section taken on the line 5—5 of Fig. 2.

Referring to the drawing, 10 designates as 35 an entirety a horizontal tubular body of the sprinkler head, and 11 an integral nozzle on the upper side of the body 10 having a conoidal spray chamber 12 therein and formed with a discharge orifice 13 in its upper end. The body 10 and nozzle 11 may be, and preferably are, formed as a single 40 casting. One end of the body member 10 is enlarged diametrically and internally threaded as shown at 14 to couple with the male member of a hose section, and the other end of the body member 10 is externally threaded 45 as shown at 15 to couple with the female member of another hose section.

The bore of the body member is preferably 50 machined through a portion of its length forming a low annular shoulder or stop 16 between the machined and the rough portions

of the surface of the bore; and in the casting operation there are formed in opposite sides of the bore longitudinal grooves 17 and 17' that are closed at one end and at their other ends open through ports 18 and 18' into the 55 lower portion of the spray chamber 12 substantially tangentially of the circular wall of the latter. By reference to Figs. 3, 4 and 5, it will be seen that the grooves 17 and 17' are longitudinally offset from each other and 60 extend in opposite directions from their closed to their ported ends.

Within the finished or machined portion of the bore of the body member 10 is driven with a tight fit a tube section or sleeve 19 of sufficient length to underlie and form the inner end wall or floor of the spray chamber 12. This sleeve 19 is driven in until it abuts the shoulder 16 as a stop, and in this position it 65 covers the major portion of the open side of each of the grooves 17 and 17', leaving, however, the closed end portion of each groove in free communication with the bore of the body member, as clearly shown in Fig. 5.

By reason of this construction the water 70 in the body member flows freely through the ducts 17, 17' and their tangential ports 18, 18', into the spray chamber 12 where it receives a whirling action and is discharged in the form of a whirling spray through the discharge orifice 13.

The sprinkler head may be provided with a suitable support therefor such as the winged base plate 20, this latter being preferably of 75 sheet metal and formed with a raised central portion comprising a seat or saddle 20' (Fig. 2) that is apertured to receive integral lugs 21 cast on the lower side of the body member, which lugs may be riveted over to firmly secure the casting to its support, as shown in 80 Figs. 2 and 3.

From the foregoing it will be seen that the 85 entire sprinkler head, exclusive of its support, comprises only two parts, namely, the body member and nozzle which may consist of a single casting, and the interfitting sleeve which forms the bottom wall or floor of the spray chamber and cooperates with the grooves 17, 17' in directing the water from op- 90 100

posite ends of the body member tangentially into the spray chamber.

I claim as my invention:

1. A sprinkler head comprising a horizontal tubular body, a nozzle on the upper side of said body having a spray chamber therein, and a tube section snugly fitting the bore of the tubular body and forming the floor of the spray chamber, the sprinkler head having a port or ports opening into the lower portion of the spray chamber exteriorly of and partly defined by said tube section.
2. A sprinkler head comprising a tubular body provided on its side with a projecting nozzle having a conoidal spray chamber therein and a discharge orifice at its outer end, and a tube section having a driving fit in the bore of the tubular body and forming the inner end wall of the spray chamber, the sprinkler head having a port or ports opening tangentially into the lower portion of the spray chamber exteriorly of and partly defined by said tube section.
3. A sprinkler head comprising a tubular body provided with grooves in the inner surfaces of its side walls and a projecting nozzle on one side having a discharge orifice at its outer end and a spray chamber therein communicating with said grooves, and a tube section snugly fitting the bore of the tubular body, forming the inner end wall of the spray chamber and covering portions of said grooves to form ducts leading from the bore of the tubular body and opening tangentially into the lower portion of the spray chamber.
4. A sprinkler head comprising a tubular body, a nozzle on the side of said body having a spray chamber therein and a discharge orifice at its outer end, said body having formed in opposite sides of its bore oppositely extending grooves closed at their inlet ends and ported at their outlet ends to said spray chamber, and a tubular section in the bore of said body member partially covering the open sides of said grooves and forming with the latter flow ducts leading from said bore into said spray chamber.
5. A sprinkler head comprising a tubular body, an integral nozzle on the upper side of said body having a spray chamber therein and a discharge orifice at its upper end, said body having formed in opposite sides of its bore longitudinally offset oppositely extending grooves closed at their inlet ends and tangentially ported at their outlet ends to the lower end of said spray chamber, and a tubular section snugly fitted in the bore of said body member partially covering the open sides of said grooves and forming with the latter flow ducts leading from said bore into said spray chamber.

HARRY E. MENG.
